UNITED STATES PATENT OFFICE

2,334,772

MINING MACHINE

Robert K. Jeffrey, Columbus, Ohio, and Lewis E. Mitchell, deceased, late of Columbus, Ohio, by Richard D. Nichols, administrator, Columbus, Ohio, assignors to The Jeffrey Manufacturing Company, a corporation of Ohio

Original application May 6, 1938, Serial No. 206,448. Divided and this application June 19, 1941, Serial No. 398,788

4 Claims. (Cl. 262—28)

This invention relates to a mining machine and particularly to the construction of the main or truck frame, and associated hydraulic motor means for swinging a turntable.

An object of the invention is to provide an improved main or truck frame for a mining machine which is of rugged construction and which incorporates as a rigid or integral part thereof hydraulic motor means for swinging the turntable.

Another object of the invention is to provide rugged but simple hydraulic motor mechanism for swinging a turntable of a mining machine.

A further object of the invention is to provide a mining machine with an improved truck or main frame and associated hydraulic motor means for swinging the turntable which is compact in arrangement.

Other objects of the invention will appear hereinafter, the novel features and combinations being set forth in the appended claims.

This application is a division of our application Serial No. 206,448, filed May 6, 1938, for an improvement in Mining machines, which matured into Patent No. 2,263,779, November 25, 1941.

In the accompanying drawing,

Fig. 1 is a plan view showing a mining machine incorporating the structure of our invention;

Fig. 2 is a plan view of the truck of said mining machine with parts shown in section; and

Fig. 3 is an enlarged sectional view of the mechanism for connecting a piston rod of a hydraulic motor to an operating rack.

In Fig. 1 of the drawing there is illustrated diagrammatically a mining machine which incorporates the structure forming the subject-matter of the invention herein claimed. The mining machine is disclosed in full detail in our parent application above identified, of which this application is a division, and so no attempt will be made to describe it in detail except as to those parts forming the subject-matter herein claimed.

Said mining machine includes a truck 45 which supports a turntable 71 on which is mounted for adjustment in a vertical plane a supplementary frame 100 which has a forwardly extending neck 109 carrying a turnover head mechanism 159 which provides for various adjustments of kerf cutting mechanism 160. Extending rearwardly from and supported by the truck 45 is a platform 545 which carries a considerable amount of mechanism which per se is not pertinent to the invention herein claimed.

The truck 45 comprises a main frame formed by longitudinally extending frame members 46, 46 which are laterally spaced-apart and between which extend transversely extending forward plate 47 and transversely extending rearward plate 48 and intermediate transversely extending bolster members 49 and 50. All of said main frame members 46 to 50, inclusive, are rigidly attached together to form a strong body or main frame for the truck 45. Said main frame is supported upon a forward axle 51 and a rear axle 52, which axle 51 is slidably journaled in adjustable journal boxes 53, 53 which may be longitudinally adjusted by adjusting screws 54, 54 to adjust the tension of the driving chain. To assure movement of the axle 51 in parallelism, the adjusting screws 54, 54 are connected to rotate together by chain and sprocket mechanism 55.

The rear end axle 52 is rigidly journaled to the main frame of the truck 45 by appropriate journal bearings 56, 56. The axles 51 and 52 are provided with appropriate driving and supporting track engaging flanged wheels 57, all of which are keyed to respective axles 51 and 52. The axles 51 and 52 are connected to rotate in unison by chain and sprocket mechanism 59. It is thus evident that any driving force supplied to axle 52 will be transmitted to all four of the wheels 57, thereby insuring a maximum of traction for propelling the mining machine, which is particularly desirable during sumping operations.

It is of course, evident that the flanged wheels 57 are adapted to ride upon rails in a mine either for transporting the mining machine from one place to another, or for supporting said mining machine while performing a mining operation. While we prefer this track mounted type of truck, said truck may be mounted in any other desired manner, as upon endless treads, to operate in a trackless mine room.

In addition to those elements above described, the truck 45 also includes a top plate 70 which is rigidly attached to the frame members 46, 47, 48, 49 and 50. The turntable 71 is mounted upon the truck for swinging movement in a horizontal plane or about an upright axis which passes through the center of a casting or pedestal 75 which is attached to said turntable and which extends downwardly through a central opening in said main frame seen in Fig. 2 of the drawing. To provide for swinging movement of the turntable 71 about its upright axis with respect to the truck 45, the lower portion of the casting 75 is provided with a pair of spaced integral gears

79 with which co-operate a pair of racks 80 and 81 having spaced top and bottom teeth. This construction provides for very large bearing area between the gears 79 and racks 80 and 81, which is particularly useful to transmit turning movement to the turntable 71 when a mining machine is making a horizontal arcuate cut.

To apply turning movement to said turntable 71 through the racks 80 and 81, said racks 80 and 81 are connected to hydraulic piston motors 82 and 83, respectively, the structures of which are similar and thus a description of motor 83 will apply to both. Said motor 83 comprises a cylinder 84 formed as an integral part of one of the frame members 46 and supplied with a removable cylinder head 85. Within the cylinder 84 is a piston 86 provided with appropriate piston rings and rigidly attached to a piston rod 87 which extends through the bottom of the cylinder 84 and is provided with a fluid tight stuffing box 88 which includes an externally threaded bushing 89. By having both motors 82, 83 on the same side of the machine, a single casting serves a plurality of functions, in that such casting has a frame portion 46, and the cylinders are reinforced by being connected together and to the frame member 46. This particular arrangement also provides for a rugged and compact unit which conserves space which is always a consideration in a mining machine which must be capable of operation in relatively low seam coal. The frame member 46 containing said motors 82 and 83 rigidly connects bolster members 49 and 50 on opposite sides of the central opening into which the pedestal 75 extends.

In order to effect a connection between the piston rod 87 and the rack 81 to transmit the force of the motor 83 to move said rack 81 and yet to prevent the lateral thrusts on the rack 81 being transmitted to the piston rod 87, stuffing box 88 and the piston 86 of the motor 83, we provide a novel connection now to be described. The rack 81 is provided with a boss 90 which is internally threaded with square threads at 91. The free end of the piston rod 87 is provided with co-operating square threads 92 which mesh with said threads 91. The threads 91 and 92 insure axial movement of the piston rod 87 and the boss 90 together without lost motion, but a restricted amount of lateral movement is permitted between the boss 90 and the piston rod 87. Therefore any lateral thrust on the rack 81 will be taken by a bearing plate 93 which is carried by the bolster 50 and will not be transmitted to the piston rod 87. It is, of course, understood that a similar connection is provided between the rack 80 and the piston rod of motor 82.

The hydraulic piston motors 82 and 83 are employed to swing the turntable 71 relative to the main or truck frame 45. This operation may be performed either while the kerf cutter 160 is cutting a horizontal kerf or while it is being positioned to cut any type of kerf. The compact arrangement of the hydraulic motors 82 and 83 is such as to consume a minimum of space consistent with their great power. By forming the cylinders of said motors integral with the truck or main frame, not only is there a conservation of space but there is also a conservation of material and a maximum of strength provided. In the preferred embodiment of the invention where the machine is mounted upon wheels 57 it is desirable that the hydraulic motors 82 and 83 ex-

tend laterally of the center line of the mining machine and preferably, as illustrated, between the forward and rearward pair of spaced-apart traction means. However, where other types of traction means, such as endless crawlers, are employed, it is evident that other arrangements may be made while preserving at least some of the advantageous features of our invention, such as the integral or rigid construction of the hydraulic motors with the truck or main frame.

Obviously those skilled in the art may make various changes in the details and arrangement of parts without departing from the spirit and scope of the invention as defined by the claims hereto appended, and we therefore wish not to be restricted to the precise construction herein disclosed.

Having thus described and shown an embodiment of our invention, what we desire to secure by Letters Patent of the United States is:

1. In a mining machine, the combination with a main frame, of a turntable mounted on said frame for adjustment about an upright axis, a pinion carried by said turntable, a rack meshing with said pinion, a hydraulic piston motor for operating said rack, and means loosely connecting said rack and piston motor constructed and arranged to prevent any lateral thrust on said rack being transferred to the piston motor.

2. In a mining machine, the combination with a main frame, of a turntable mounted on said frame for adjustment about an upright axis, a pinion carried by said turntable, a rack meshing with said pinion, a hydraulic piston motor for operating said rack, and means loosely connecting said rack and piston motor constructed and arranged to prevent any lateral thrust on said rack being transferred to the piston motor and including cooperating teeth on said rack and the piston rod of said motor formed of different size to permit relative radial movement while preventing relative longitudinal movement.

3. A mining machine including a main frame, traction means for said main frame for moving it rectilinearly, a turntable mounted above said main frame for swinging movement, said main frame including parts rigidly attached together and forming a central opening, said turntable having an operating pedestal extending downwardly through said opening, mechanism positioned within said opening for swinging said pedestal, and motor means for operating said mechanism including a part formed integral with a member of said main frame which extends across one side of said opening and rigidly attaches spaced parts of said main frame on opposite sides of said opening, said member being constructed to constitute part of said main frame.

4. A main frame for a mining machine comprising rigidly attached members, means connected thereto adapted to receive traction means for the main frame, said attached frame members being formed to provide a central opening adapted to receive a downwardly extending pedestal of a turntable, said main frame including as a part thereof a member connecting other members on opposite sides of said opening which said member includes as an integral part thereof a part of a motor.

ROBERT K. JEFFREY.
RICHARD D. NICHOLS,
Administrator of the Estate of Lewis E. Mitchell,
Deceased.
